UNITED STATES PATENT OFFICE

HAROLD F. ELLIOTT, OF PALO ALTO, CALIFORNIA, ASSIGNOR, BY MESNE ASSIGNMENTS, TO RADIO CORPORATION OF AMERICA, OF NEW YORK, N. Y., A CORPORATION OF DELAWARE

SELECTIVE RADIOPICK-UP

Application filed April 21, 1928. Serial No. 271,862.

This invention relates to radio communication, and especially to a system whereby radio signals may be received without interference.

5 Since there may be a large number of closely spaced transmitting stations operating simultaneously, each carrying signals at different frequencies, it is important to make it possible to receive signals from one station to 10 the exclusion of the others, by making the receiver discriminatory with respect to frequency. This has been accomplished by the provision of tunable circuits, which can be made resonant to the frequency at which reception is desired; but experience teaches 15 that such resonant circuits, even if multiplied, can yet pass a sufficient volume of interfering signals to produce disturbance, especially if the interfering stations are powerful or near- 20 by.

It is one of the objects of my invention to make it possible readily to select the station from which reception is desired, to the substantial exclusion of the other stations that 25 may be simultaneously transmitting, and especially to accomplish this result by the aid of simple and inexpensive apparatus.

It is another object of my invention to provide a unit control system that can operate 30 the various tunable circuits in unison.

The ideal condition for selectivity would be one in which a narrow band of frequencies alone can pass to the receiver, for example, a band of about 10,000 cycles, which band 35 can be moved at will from one end of the range of reception to the other. With the aid of my invention this ideal condition can be closely approximated.

In connection with the superheterodyne 40 system of radio reception, my invention is particularly advantageous. In such superheterodyne systems, the carrier frequency that is received is combined with a frequency either above or below it to produce a beat 45 frequency of intermediate value, but above the range of audibility. This beat frequency then carries the signals, which can be detected and amplified at the intermediate frequencies, and then later, again detected and 50 passed to audio frequency amplifiers. It is

evident, in such a system, that the same beat frequency could be produced by another interfering station which is transmitting on a carrier wave displaced from the frequency of the local oscillator by the same amount as 55 the frequency of that local oscillator is displaced from the frequency of the desired station. Thus it is sometimes necessary to re-adjust the local oscillator, whereby this beat frequency can no longer occur from the interfering station. With the aid of my invention, this disadvantage is overcome, and it is possible to adjust the frequency of the oscillator to its desired value once and for all when a desired station is to be received, and 60 the interfering signals are suppressed. 65

It is still another object of my invention to improve in general, radio receivers in which electronic emission amplifiers or detectors are used. 70

My invention possesses many other advantages, and has other objects which may be made more easily apparent from a consideration of several embodiments of my invention. For this purpose I have shown a few forms in the drawings accompanying and forming part of the present specification. I shall now proceed to describe these forms in detail, which illustrate the general principles of my invention; but it is to be understood 75 that this detailed description is not to be taken in a limiting sense, since the scope of my invention is best defined by the appended claims. 80

Referring to the drawings: 85

Figure 1 is a wiring diagram of one form of my invention;

Fig. 2 is a graph illustrating the selectivity that may be expected with the aid of my invention; and 90

Fig. 3 is a form of my invention embodied in connection with a superheterodyne receiver.

In Fig. 1, I show an open pick-up circuit, including the elevated conductors 11, a loading inductance 12, a variable condenser 13, a variable resistor 14 and the ground connection 15. By the aid of the variable condenser 13, this pick-up system can be tuned to the frequency at which reception is desired. The 100

variable resistance 14 is preferably tapered as indicated, to a maximum value of about 400 ohms. The drop across the resistance is the useful signalling voltage received by the pick-up system. It is evident that interfering signals, which are not in tune with the pick-up system, do not cause as large a resistance drop in resistance 14 as the desired signals. Furthermore, by varying the resistance 14, the amount of energy by-passed thereby can be regulated, whereby a volume control is secured.

In order to amplify the received signals, use can be made of any desired form of amplifiers or series of amplifiers. In the present instance, I indicate an electronic emission device 16 that is utilized as an amplifier for this purpose. However, any number of such devices can be used in cascade. It includes an evacuated vessel having therein an electron emitting electrode 17, such as a filament adapted to be heated by the passage of an electric current; and a plate electrode or anode 18 which receives the electrons emitted from electrode 17. This plate electrode can be maintained at a positive potential with respect to the filament 17, as by aid of a battery 19, which is connected in an external circuit between these two electrodes. The space current between the filament 17 and the anode 18 is controlled by the control electrode 20, usually in the form of a grid interposed between the filament 17 and the anode 18. It has been found that even minute variations in potential difference between the electrodes 17 and 20 will cause correspondingly great variations in the electron flow from the filament 17 to anode 18. It is this effect which is utilized for amplification.

The input electrodes 17 and 20 of amplifier 16 are arranged to be affected by the potential differences existing across the resistance 14, whereby the current flowing in the external circuit connecting the electrodes 17 and 18 can be varied in accordance with these signals.

This output current can be passed through succeeding stages of amplifiers and detectors indicated by the rectangle 21, and finally to a translating device, 22, such as phones or a loudspeaker.

My invention relates more particularly to the manner in which the signalling potential differences are impressed between the electrodes 17 and 20. First of all, there is a tunable series circuit, comprising for example an inductance 23 and the variable condenser 24. One terminal of this circuit connects to the upper end N of the resistance 14. The point N¹ at the other end of this series tuned circuit is therefore substantially of the same potential as the point N for electrical energy of the frequency that is in tune with the tuned circuit 23-24. In other

words, N and N¹ can be called potential nodal points, for the frequency of reception, if the circuit 23, 24 is tuned to that frequency of reception. For any other frequency, there will be a potential difference between points N and N¹, the value depending upon the extent of departure from resonance frequency.

From point N¹ to ground 15 there is another series tunable circuit, including the series circuit formed by a variable condenser 25 and an inductance coil 26. The ground 15 is therefore another nodal point. Across this latter inductance coil 26 are connected the two input electrodes 17 and 20, whereby the potential differences across the inductance coil, are effective to control the space current in amplifier 15. This potential difference is a maximum for the frequency to which circuit 25-26 is tuned and is less for all other frequencies.

A resistance 27 can be connected between point N¹ and ground 15. Since this resistance is connected across the series tuned circuit 25-26, it is evident that it connects between two nodal points, and therefore there will be only a small drop across this resistance for the frequency of reception. However, for all other frequencies, some of the energy will be by-passed through this resistance 27.

Paralleling the resistance 27 are two tuned series circuits, comprising respectively inductance 28 and variable condenser 29; and inductance 30 and variable condenser 31. These tunable circuits are tuned respectively to a frequency a little higher and a little lower than the frequency at which reception is desired. For example, circuit 28-29 can be tuned to a frequency about ten or twenty kilocycles below the desired frequency of reception; while circuit 30-31 may be tuned to a frequency ten or twenty kilocycles above the desired frequency of reception.

The result is that in connection with the band of frequencies having as limits the resonant frequency of the two tuned circuits 28-29 and 30-31, these circuits shunt interfering signals which are outside of that band. For example, if it be desired to receive signals carried on waves of 1,000 kilocycles, circuit 28-29 should be tuned to a frequency of about 980 kilocycles, while circuit 30-31 should be tuned to a frequency of about 1020 kilocycles. With such tuning, the response of the receiver is a maximum for the desired frequency, and it is a minimum at the frequency of resonance of circuits 28-29 and 30-31.

This is graphically indicated in Fig. 2, wherein the line 32 represents the actual resonance conditions, secured by the system of Fig. 1; and the dotted line 33 represents a so-called ideal, which the system approaches. It is seen that the peak of curve 32 representing the desired carrier frequency, and

the narrow band adjacent to it affect the receiver most strongly. However, interfering signals fall considerably below the peak and therefore their audibility is lessened. It is thus seen that the effect of the use of the two tuned circuits is to compress the actual curve of resonance 32, and thereby to sharpen the tuning.

In order to make this system operate most effectively. It is of course desirable to keep the circuits 28-29 and 30-31 tuned to the proper frequencies for any frequency of reception. This can be accomplished by a single dial tuning mechanism, in which condensers 13, 24, 25, 29, and 31 are simultaneously tuned so as to keep their respective circuits tuned to the proper relative frequencies. This can readily be accomplished for example by the aid of mechanism disclosed in my prior Patent 1,707,948, granted April 2, 1929, and entitled "Tuning system". Furthermore, in order to ensure against any stray effects, the tuned circuits can be encompassed in grounded metal shields. For example, circuit 23-24 can be closed in a grounded shield 34; and circuits 28-29 and 30-31 can be respectively shielded by grounded shields 35 and 36; finally the amplifier 16 with its associated circuits can likewise be shielded, as indicated by the dotted line 37.

The fact that all the tuning elements of the system can be readily controlled by a single actuating member is of considerable importance, for by its aid, the proper relationship between the circuits 28-29 and 30-31 and the remaining circuits can always be maintained, without the necessity of tedious manipulation. This feature of unit control, I indicate by a series of dotted lines 38 converging to a common point from the various tuning devices, and leading to the legend, "Unit control".

The principle of by-passing particularly annoying interfering oscillations is especially adaptable in connection with superheterodyne reception. Such a scheme is shown for example in Fig. 3.

In this case, a loop pick-up circuit is illustrated, including the loop or coil 38¹, and a tuning condenser 39 placed in series with the coil 38¹. The other side of the loop can be grounded as illustrated at 40. This makes point 41 a nodal point, and from that point to ground 40, there is another tuned circuit including the variable condenser 42 and the coil 43. The circuit 38¹-39 as well as the circuit 42-43 should both be tuned to the desired frequency of reception. Furthermore, a tapered variable resistance 44 can be connected across the tuned circuit 38¹-39 to provide a volume control.

The electronic emission amplifier 45 has its input electrodes connected across the coil 43. A battery or other source of potential 46 is utilized to provide a negative bias on the

grid electrode 47; and the output circuit includes the plate or anode 48, the coupling coil 49 and the plate battery 50. The amplified impulses present in coil 49 are transferred to a tunable circuit, including the secondary coil 51 and the variable condenser 52. This tunable circuit affects the first detector tube 53. A local oscillator system 54 also affects the input of the tube 53 in order to change the carrier frequency from that of the station from which the signals are received, to an intermediate value. This system 54 is shown in the present instance as comprising an electronic emission device 55 having its input and output circuits coupled together, and capable of being adjusted for varying frequencies by the aid of the variable condenser 56 which tunes a circuit comprising that condenser and coil 57. This latter coil also serves as a means for transferring the oscillations to the input side of the device 53, by being inductively coupled to the coil 58 located in the connection to the grid electrode of device 53. Device 53 can be arranged to act as a detector by means of a suitable grid bias battery 59. The output circuit of the first detector 53 that connects the anode 60 to the electron emitting filament 61, includes the primary coil 62 and a plate battery 63. In this external circuit flows a current that has a frequency equal to the beat frequency produced by the action of oscillator 54 upon the received oscillations in the pick-up circuit. This beat frequency is intermediate in value between the carrier frequency received, and the audio frequency modulations thereof.

As thus far described, this system is quite similar to that of an ordinary superheterodyne system. The intermediate frequency waves are passed to an intermediate frequency amplifier 64 coupled to the output of the first detector 53. This amplifier can comprise one or more stages of electronic emission amplifiers, all permanently tuned to a definite predetermined intermediate frequency, which can always be secured by proper manipulation of the oscillator system 54.

From the intermediate frequency amplifier 64, the amplified intermediate frequency energy can be passed to a second detector and audio frequency amplifier 65. From there the amplified audio frequency signaling currents can be passed to a translating device, such as a loudspeaker or phones 66.

Now let us assume that it is desired to receive from a station which is transmitting on 1,000 kilocycles. In this case, circuit 38¹-39, 42-43, and 51-52 should be all accurately tuned to that frequency. The oscillator 54 can be tuned to a frequency either above or below 1,000 kilocycles to give a beat frequency of say 47.5 kilocycles. For this purpose it can be tuned for example to 952.5 kilocycles. This gives an intermediate frequency of 47.5

kilocycles and the intermediate frequency amplifier 64 may be designed to operate at this frequency.

These intermediate frequency amplifiers of course are usually arranged to pass a 10,000 cycle band around 47.5 kilocycles in order to secure proper reproduction, as is well understood. However, let us assume that there is an interfering station sending strong signals at a frequency of 905 kilocycles. This may get through the tuned circuits referred to, with sufficient strength to produce a beat frequency with the frequency of oscillator 54 of the same value as before; that is, 47.5 kilocycles. In the past, in order to avoid such an interference, the frequency of the oscillator 54 was increased above 1,000 kilocycles so as to produce 1047.5 kilocycles, still giving the same beat frequency of 47.5 kilocycles. In this way the 905 kilocycle station could be shut out. But such a shift in frequency of the oscillations produced by the oscillating system 54 may have the effect of making it easy for another station to interfere. For example, if there should be a station sending strong signals nearby, or at a short distance, on 1095 kilocycles, this would combine with the frequency of the oscillator 54 to give the same beat frequency of 47.5 kilocycles in the intermediate frequency amplifier.

I overcome this interfering effect by the addition of a circuit between nodal point 41 and ground 40, which comprises a tunable circuit having a variable condenser 66¹ and an inductance coil 67. This circuit is tuned to the frequency of the interfering signals and offers an effective by-pass for the interference without appreciably reducing the signals to be received. For example, the oscillator 54 can be set so as to be always 47.5 kilocycles (or any intermediate frequency desired) below the frequency of the station from which signals are to be received. In that case, then circuit 66¹—67 must be correspondingly tuned 95 kilocycles below the frequency to be received, since the only interfering station that could get through to affect the system would be a station sending out waves of a frequency of 95 kilocycles below the frequency of the station from which signals are to be received. This interfering energy, however, will be by-passed through the circuit 66¹—67, and will not affect the amplifier 45, nor the intermediate frequency amplifiers 64.

As in the case illustrated in Fig. 1, all of the variable condensers or other variable tuning devices can be operated from a common control. This is indicated by the dotted line 68, leading to the legend "Unit control". In order to increase selectivity and to ensure against stray affects, the circuits can also be shielded by grounded shields, such as indicated by dotted rectangles 69, 70, and 71.

I claim:

1. In a superheterodyne system of radio reception, in which there is a local oscillator the frequency of which is adjustable whereby a beat frequency of a set constant value is secured for any frequency of reception, a tunable pick-up circuit including a resistor in series therewith, an electronic emission amplifier device having input electrodes and a tunable circuit having an inductance connected with said electrodes, said last named circuit being connected across said resistor, a second tunable circuit connected in parallel with said last named tunable circuit for bypassing energy from said pick-up circuit, and a common control means arranged for simultaneously tuning the pick-up circuit, for varying the frequency of the oscillator to provide said constant beat frequency, and for tuning the energy by-pass circuit to a value such that it is resonant at all times to a frequency other than the signal frequency which is capable of producing the same constant beat frequency.

2. In a radio receiving system, the combination of a pick-up circuit including a series connected inductance, variable condenser and variable resistor, means for applying signal potentials to said pick-up circuit, a second inductance, a second variable condenser and a second resistor connected in series across said variable resistor, a third variable condenser, and a third inductance connected in series across said second resistor, a signal amplifier including an electronic emission device having input electrodes connected with said last named inductance and having an output circuit, said circuits being tunable by means of said variable condensers to establish nodal points of potential at one terminal of each of said resistors.

3. In a radio receiving system, the combination of pick-up circuit including an inductance, a variable condenser and a variable resistor connected in series, means for applying signal potentials to said pick-up circuit, a second inductance, a second variable condenser and a second resistor connected in series across said variable resistor, a third variable condenser and a third inductance connected in series across said second resistor, an electronic emission device having input electrodes connected with said last named inductance and having an output circuit, said circuits being tunable by means of said variable condensers to establish nodal points of potential at one terminal of each of said resistors, and a pair of series resonant devices connected in parallel with said second named resistor, each of said devices being adapted to be tuned to a frequency differing from the frequency to which said pick-up circuit is tuned.

4. In a radio receiving system, the combination of a pick-up circuit including an

inductance, a variable condenser and a resistor connected in series, a pair of tunable series circuits connected in parallel with said resistor, each of said tunable series circuits including an inductance, and an electronic emission device having input electrodes connected with one of said inductances and having an output circuit.

5. In a radio receiving system, the combination of an input circuit tunable for the reception of signal waves through a predetermined band of signal frequencies, said input circuit having a plurality of potential nodal points for the frequency of reception, 10 two of said nodal points being in the high potential side and a third nodal point being in the low potential side of said input circuit, a tunable series circuit connected between said first two nodal points, a second series 15 tunable circuit connected between one of said nodal points and said third nodal point in the low potential side of the input circuit, said last named tunable circuit including a reactance tuning device, an electronic emission 20 device having input terminals connected across said reactance tuning device, and a signal output circuit for said electronic emission device.

25 In testimony whereof I have hereunto set
30 my hand.
